F. H. GILBERT,

SACK HOLDER.

APPLICATION FILED JUNE 2, 1920.

1,402,227.

Patented Jan. 3, 1922.

UNITED STATES PATENT OFFICE.

FRANK H. GILBERT, OF RIDGEFIELD, WASHINGTON.

SACK HOLDER.

1,402,227.

Specification of Letters Patent.

Patented Jan. 3, 1922.

Application filed June 2, 1920. Serial No. 386,006.

To all whom it may concern:

Be it known that I, FRANK H. GILBERT, a citizen of the United States, and a resident of Ridgefield, county of Clarke, State of Washington, have invented a new and useful Improvement in Sack Holders, of which the following is a specification.

My invention has for its object the providing of a durable and efficient sack-holding mechanism which is composed of standard parts conveniently manufactured at reasonable cost, and which, furthermore, is adapted for being readily applied to hoppers of different sizes.

It is furthermore my object to provide simple means for supporting my sack holder from any vertical support and which means will hold the hopper in proper relation to such support.

I attain the above specified features and others incidental thereto by the novel combination of parts constructed and operating as hereinafter described, and illustrated in the accompanying drawings.

In the latter, Fig. 1 is a perspective illustrating a metal hopper provided with my sack-holding mechanism and supported as in practice from a suitable support;

Fig. 2 is a partial view on a larger scale, of the front of the hopper showing my sack-holding mechanism as arranged for holding the sack;

Fig. 3 shows substantially a view like the preceding figure, except in this instance the sack-holding mechanism has been operated to release the sack;

Fig. 4 is a transverse section of a wall from which my sack holder is suspended, and of the hopper of my sack-holder and illustrates the means preferably provided by me for supporting the hopper in its proper position with regard to its support, so as to properly suspend the sack;

Fig. 5 is a partial rear elevation of the hopper further illustrating said hopper supporting device; and

Fig. 6 is a detail showing a section of the front hopper wall and an edge view of the latch plate of my sack-holding mechanism pivoted to said wall.

a is a metal hopper provided on its opposite ends and its front with the parts constituting my sack-holding mechanism. The latter consists of bars *b* attached to said ends, and made with inturned ends *c* which are adapted to serve as journal pins (*d*) on

which hollow axles *e* are journaled. The axles are provided with sack holding prongs *f* and an ear *g* serving as a crank element. To the front side of the hopper *a* is pivoted 60 a latch-plate *h* provided with lips as *i* (see Fig. 6) serving as spacing elements; the latch plate *h* is rotatable on a pin *j* in a plane parallel with the adjacent side of the hopper from which it is spaced so that the 65 links *k*, *k'* by which the chains *l*, *l'* are connected with the latch-plate *h* may operate on the under side of the latter, thus being out of the way, and preventing any interference of the parts. The latch-plate *h* is also made 70 with an upturned lip *m* which serves as a handle for rotating the latch-plate against the tension of the spring *n*. The latter is fastened to the hopper at one end, as at *o*, and the opposite end being attached to a 75 link *p* pivoted at *q*. The latch-plate *h* is provided with a pin *r* which when the sack-holding mechanism is in its sack releasing position serves to maintain the spring *n* in an operative state as illustrated in Fig. 3; 80 without similar means the spring *n* would be liable to assume a position which would render the latch-plate *h* difficult to operate for restoring the sack holding means into their sack holding states.

The chains *l*, *l'* are connected by links *s*, *s'* with the crank elements *g*; hence by using links as *s*, *s'*

The chains *l*, *l'* run through guide elements *t*, *t'*. When the parts of my sack holding mechanism are arranged as shown in Fig. 2, said mechanism is adapted for having a sack suspended therefrom. Note that the links *k*, *k'* are located on the opposite sides of the pivot pin *j* of the latch- 90 plate *h*, and that the chains *l*, *l'* pull substantially in a straight horizontal line, thus imposing no work upon the coil-spring *n* in holding the parts in their sack holding position. By seizing the handle *m* of the 100 latch plate *h* and rotating the latter counterclockwise, the latch holding mechanism becomes arranged in its sack releasing position as illustrated.

In order to support the hopper in proper 105 position relatively to the support from which it is suspended, I fasten to the back wall *u* of the hopper a stiffening board *v* on which are secured suspending straps *w*; and in the middle of the board *v* I hinge a 110 prop *x* on which is mounted a bearing plate *y* having a perpendicular ear at each side

through which the inturned ends of the prop α extends, and having a perpendicular ear y' at the top through which a rod z extends suspending by a chain 3 from the board v . On the rod z is threaded a nut 4 by the adjustment of which the prop α is raised and lowered so as to properly support or prop up the hopper u with regard to its support. flexible connections connecting said crank elements with said latch plate, said flexible connections passing through said guides, said flexible connections including links fastened to said crank elements, the points of attachment of said flexible connections to the latch plate being so located as to be in straight alinement with the pivotal center of the hinged connection of the

I claim:

1. In a sack holder, a hopper, a pair of shafts rotatably supported on the opposite ends thereof, sack-holding pins carried by said shafts, a crank-element on each shaft, a spring-controlled latch-plate pivoted on the hopper between the ends on which said shafts are journaled, said latch-plate being rotatable in a plane parallel with the adjacent side of the hopper, means spacing such latch-plate from said hopper side, guides provided on said hopper side at each end, flexible connections connecting said crank elements with said latch plate, said flexible connections passing through said guides, said flexible connections including links fastened to said crank elements, the points of attachment of said flexible connections to the latch plate in one position of the latter being so located as to be in straight alinement with the pivotal center of the latch-plate.

2. In a sack holder, a hopper, a pair of shafts rotatably supported on the opposite ends thereof, sack-holding pins carried by said shafts, a crank-element on each shaft, a spring-controlled latch-plate pivoted on the hopper between the ends on which said shafts are journaled, said latch-plate being rotatable in a plane parallel with the adjacent side of the hopper, means spacing such latch-plate from said hopper side, guides provided on said hopper side at each end, flexible connections connecting said crank elements with said latch plate, said flexible connections passing through said guides, said flexible connections including links fastened to said crank elements, the points of attachment of said flexible connections to the latch plate being so located as to be in straight alinement with the pivotal center of the latch-plate in one position of the latter, the ends of said flexible connections attached to said latch-plate being located on the under side of the latter and on opposite sides of its pivot pin.

3. In a sack holder, a hopper, a pair of shafts rotatably supported on the opposite ends thereof, sack-holding pins carried by said shafts, a crank-element on each shaft, a spring-controlled latch-plate pivoted on the hopper between the ends on which said shafts are journaled, said latch-plate being rotatable in a plane parallel with the adjacent side of the hopper, means spacing such latch-plate from said hopper side, guides provided on said hopper side at each end,

4. In a sack holder, a hopper, a pair of shafts rotatably supported on the opposite ends thereof, sack-holding pins carried by said shafts, a crank-element on each shaft, a latch-plate pivoted on the hopper between the ends on which said shafts are journaled, said latch-plate being rotatable in a plane parallel with the adjacent side of the hopper, guides provided on said hopper side at each end, flexible connections connecting said crank elements with said latch-plate, said flexible connections passing through said guides, a tension spring connected to said latch-plate serving to hold the sack holding device in their sack-holding position, means whereby said spring is restrained to its active position during the rotation of said latch-plate while operating the sack holding means to release the sack.

5. In a sack holder, a hopper, a pair of shafts rotatably supported on the opposite ends thereof, sack-holding pins carried by said shafts, a crank-element on each shaft, a latch-plate pivoted on the hopper between the ends on which said shafts are journaled, said latch-plate being rotatable in a plane parallel with the adjacent side of the hopper, means spacing such latch-plate from said hopper side, guides provided on said hopper side at each end, flexible connections connecting said crank elements with said latch-plate, said flexible connections passing through said guides, said flexible connections including links fastened to said crank elements, the points of attachment of said flexible connections to the latch-plate being so located as to be in straight alinement with the pivotal center of the latch-plate in one position of the latter, the ends of said flexible connections attached to said latch-plate being located on the under side of the latter and on opposite sides of its pivot pin, a compression spring connected to said latch-plate serving to hold the sack holding device in their sack-holding position, means whereby said spring is restrained to its active position during the rotation of said latch-plate while operating the sack holding means to release the sack.

6. In a sack holder, a hopper, a pair of

- shafts rotatably supported on the opposite ends thereof, a crank-element on each shaft, a latch-plate pivoted on the hopper between the ends on which said shafts are journaled, 5 said latch-plate being rotatable in a plane parallel with the adjacent side of the hopper, means spacing such latch-plate from said hopper side, flexible connections connecting said crank elements with said latch plate, 10 said flexible connections passing through said guides, the ends of said flexible connections attached to said latch-plate being located on the underside of the latter and on opposite sides of its pivot pin.
- 15 7. In a sack holder, a hopper, a pair of shafts rotatably supported on the opposite ends thereof, a crank element on each shaft,
- a latch-plate pivoted on the hopper between the ends on which said shafts are journaled, said latch-plate being rotatable in a plane 20 parallel with the adjacent side of the hopper, means spacing such latch-plate from said hopper side, flexible connections connecting said crank elements with said latch plate, said flexible connections passing 25 through said guides, the ends of said flexible connections attached to said latch-plate being located on the underside of the latter and on opposite sides of its pivot pin, the latch-plate being adapted to overlie the 30 flexible connections in all positions of the latch plate.

FRANK H. GILBERT.
